(57) **CLAIM**

The ornamental design for a handle for cutlery, as shown and described.

DESCRIPTION

FIG. 1 is a front, top perspective view of a handle for cutlery showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a front, top perspective view thereof, shown in environmental use.

The broken lines shown in the drawings depict portions of the handle for cutlery that show no part of the claimed design.

The dot-dash broken lines forming the strap shown in FIG. 9 are for the purpose of illustrating environment and form no part of the claimed design.

1 Claim, 9 Drawing Sheets
